UNITED STATES PATENT OFFICE.

IRA C. N. SWEET, OF SANDWICH, ILLINOIS.

PUMP.

SPECIFICATION forming part of Letters Patent No. 408,547, dated August 6, 1889.

Application filed August 27, 1888. Serial No. 283,915. (No model.)

To all whom it may concern:

Be it known that I, IRA C. N. SWEET, a citizen of the United States of America, residing at Sandwich, in the county of De Kalb and State of Illinois, have invented a certain new and useful Improvement in Pumps, of which the following is a specification.

Referring to the accompanying drawings, in which similar reference-letters indicate the same or corresponding parts, Figure 1 is a vertical section of a pump containing my improvement, showing the air-valve locked out of action and the water-valve in position for action. Fig. 2 is a section of the part containing my improvement, showing the water-valve locked out of action and the air-valve in position for action. Fig. 3 is a bottom plan with the valves and key complete. Fig. 4 is a bottom plan with the key, water-valve, and a portion of the air-valve device removed. Fig. 5 is a plan showing the leather to which said water-valve is attached. Fig. 6 is a modified form, shown in section, adapted to a single-valve device with the valve-seats on one and the same flange; and Fig. 7 is another modification adapted to a single-valve device, with the valve-seats arranged on separate flanges.

In a pending application for Letters Patent of the United States, filed by me the 5th day of May, A. D. 1888, Serial No. 272,938, I have shown and described a pump containing a barrel or stock A, a handle B, and a hollow plunger-rod C, supporting a chambered plunger C', and provided with a shifting-valve C², attached to an adjusting-rod C³, which extends up through the hollow plunger-rod and is capable of being locked in position by means of a set-screw c, said valve having a flexible flap c', which enables it to act as an air-valve when adjusted against its upper seat, the whole being adapted to raise water up from or force air down into a cistern, tank, or well, according as the valve is locked against its upper seat or left free to rest upon its lower seat. Without a retaining-valve said pump is capable of forcing air only a few feet below the surface of the water in the cistern or well, and the object of my present invention is to combine with it a suitable retaining-valve adapted to co-operate with the plunger both in raising water and forcing

down air, and thereby to increase the capacity and effectiveness of the pump for the purposes of its use.

To this end my present invention consists, primarily, in combining with said pump-tube and double-acting plunger, or their functional equivalents, a double-acting retaining-valve device capable of being adjusted or shifted to correspond to the adjustment of the plunger-valve, so as to act under one adjustment as a retaining-valve for the water raised, and under another adjustment as a retaining-valve for the air forced down through the pump-tube, and, secondarily, in the combination of parts composing the adjustable double-acting retaining-valve device.

The essential elements of my double-acting retaining-valve device, consisting of two valve-seats, one facing upward, or in the direction of the water-current, and the other downward, or in the direction of the air-current, two valves, one seating downward on the upwardly-facing valve-seat to act as a water-valve and the other seating upward against the other valve-seat to act as an air-valve, with means for locking either valve out of action, while leaving the other free to perform its function. The two valves may be made entirely separate from each other, or they may both be combined in one movable and adjustable member, and their adjustment or shifting is preferably effected simultaneously by the action of a single adjusting device.

The best form in which I have contemplated the application of my invention is as follows:

I construct a casting D, adapted to act as a coupling between the upper and lower parts of the pump-tube, and preferably provided with lugs and bolt-holes D', by which it may be conveniently secured to a stand or plank as a support for the pump-stock A. This casting is provided with one or two internal flanges, their number depending upon the form of valve device employed. To illustrate my invention I have shown three forms of valve device, the first consisting of two separate valves with their seats arranged on opposite sides of a single flange d, as indicated in Figs. 1, 2, 3, 4, and 5, the second consisting of a double puppet seating against separate

flanges d d' , as represented in Fig. 6, and the third consisting of a single puppet seating against flanges, as shown in Fig. 7.

Referring to Figs. 1, 2, 3, 4, and 5, e indicates the water - passage, and e' a separate air - passage through the flange d ; W , the water-valve seating down on flange d , preferably in the form of a clack, supported and hinged by a leather w , and provided with a tripping-toe t , as usual in pump-valves, and V the air-valve seating up against flange d , and preferably composed of a strip of rubber or leather extending across the under side of the air-passage and fastened at its ends to the flange d , as seen more clearly in Fig. 4. When this form of air-valve is used, I reinforce its under side by a piece of metal, and for such purpose prefer to employ a crescent-shaped strip V' , thickened at its middle between the dotted lines seen in Fig. 3 and loosely fastened at its ends to the under side of flange d by screws v v . Under both valves extends a transverse adjusting or shifting key M , the inner end of which may be centered in a lug f dependent from the flange d , and the outer end of which is centered in a large screw-hole formed through the side wall of the casting D , as shown, the key being provided with a screw-thread to tightly fit the hole. This key, in the form here shown, is constructed with two eccentric portions—to wit, one (indicated at m) having a slight degree of eccentricity to act in connection with the valve V V' , and the other (represented at m') having a larger degree of eccentricity, and preferably in the form of a crank-arm to act in connection with the valve W . A link L depending from the valve W extends around the crank-arm m' , and is of such length that when said arm is turned up it will leave said valve free to rise and fall, but when turned down will lock the valve firmly to its seat. The eccentric m when turned down permits the valve V V' to rise and fall, but when turned up locks it firmly to its seat. Both eccentrics are arranged at the same side of the key, so that when either is in position to lock its appropriate valve the other will be in such position as to leave its valve free; hence, by turning the key half round either valve may be brought into position for action and the other locked out of action, and thus the device may be at will adjusted to act as a water-valve or an air-valve. The size of the screw-hole in the casting D should be such as to permit the introduction of the eccentric portion of the key through it.

The crescent-shaped plate V' may be inserted between the key and the flange d after the key is in place and its ends then secured by screws extending into the under side of the flange.

In the forms represented in Figs. 6 and 7 both valves are combined in a single adjustable valve device acting as a combined puppet

and flap valve. In the double puppet (shown in Fig. 6) the flap V is arranged around the upper edge of that plate which seats upward—the lower plate or end of the valve device, as there shown—and the key M may be inserted through a slot in the connecting-web between the two plates, in which case the connecting-web performs the function of the link L . In the single puppet (shown in Fig. 7) the flap is also arranged around the upper edge of the valve-plate, and in this case the eccentric may be arranged above the valves, if preferred. In either form the valves must be properly guided in the manner usual with puppet-valves, and the slot in which the crank-arm works must be so proportioned that the crank-arm, when turned up, will hold the air-valve in the proper relation to its seat and the water-valve away from its seat, and when turned down, will allow the water-valve to seat and limit its upward movement so that the air-valve cannot become seated. In the puppet-valve construction the eccentric m of Figs. 1, 2, 3, 4, and 5 becomes unnecessary and is omitted.

From the above description and explanation it will readily be seen that the essential principle of my retaining-valve device consists in combining two oppositely - seating valves with means for locking either at will out of action while leaving the other free, and that such device is capable of acting as a water-valve in co-operation with any ordinary pump-plunger, and both as a water and air valve in co-operation with the double-acting plunger described in my said pending application, or with any other plunger or combination of plungers adapted to be employed at one time for raising water up and at another time for forcing air down through a pump-tube. It is also obvious that my invention, in its broad sense, is independent of the form and arrangement of the structural details, which may be greatly varied without departing therefrom, and that it may be employed in connection with any form of force or lift pump operated with a reciprocating plunger.

Having thus described the principle of my invention and the best forms in which I have contemplated its practical application, what I claim as new, and desire to secure by Letters Patent, is—

In a lift or force pump operated by a plunger, two retaining-valves, one a water and the other an air valve, in combination with a key or arm extending through the pump tube or cylinder and adapted to lock either valve at will out of action as a valve while leaving the other free to act, substantially as described.

IRA C. N. SWEET.
